UNITED STATES PATENT OFFICE

2,429,000

GRAVE VAULT

John W. Staggers, Washington, D.C.

Application February 11, 1944, Serial No. 521,984

3 Claims. (Cl. 72—7)

1

This invention relates to a grave or burial vault.

It is primarily aimed to provide a construction which may be sealed so as to be water and moisture-proof and yet be made from Portland cement or the equivalent, thus overcoming the objection to prior attempts to manufacture satisfactory burial vaults from the same material, namely, that they were not water and moisture-proof.

Another object is to provide a construction wherein the weight of the cover materially functions in the binding and sealing the cement used in producing the water and moisture-proof joint.

Further, it is aimed to provide a structure wherein the cover or closure and the container body have interfitted parts provided with novel coacting, undercut grooves filled with the binding and sealing cement.

The more specific objects and advantages will become apparent from a consideration of the description following taken in connection with accompanying drawings illustrating an operative embodiment.

In said drawings:

Figure 1 is a top or plan view of the container section of the vault;

Figure 2 is an inverted plan view of the closure or cover section of the vault;

Figure 3 is a fragmentary side elevation of a closed vault;

Figure 4 is a vertical section taken on the plane of line 4—4 of Figure 3;

Figure 5 is a detail showing the interfitting parts of the vault sections in spaced relation; and

Figure 6 is a horizontal section taken on the plane of line 6—6 of Figure 4.

Figure 7 is a fragmentary detailed sectional view showing some of the cement forced to an elevated position between the base and the rib.

Referring specifically to the drawings wherein like reference characters designate like or similar parts, the burial or grave vault shown has a container section 10 for the casket and a closure section at 11. These sections 10 and 11 are initially separate and are made from concrete using a water and moisture-proof Portland or other cement so that when the sections are set and dry or hardened, they will be impervious to moisture.

Said sections 10 and 11 are joined together by providing a continuous depending rib 12 which fits into a continuous groove 13 of the same shape, in the upper edge of the upstanding wall of the container section and which upper edge and the under surface of the cover section 11 have coplanar engagement as shown.

It is to be noted that at the base of the groove 13, it is widened to provide auxiliary undercut grooves 14 preferably semi-circular in cross section and that the rib 12 has opposed grooves,

2

similar in shape to those at 14, however, with the corner edges 16 of the rib 12 preferably cut away slightly, whereby the rib 12 is narrower at its base than above the grooves 15.

In joining and sealing the sections 10 and 11, the rib 12 occupies groove 13 and prior to the interfitting, a predetermined quantity of binding and sealing cement is applied to the groove 13 so as to form joining and sealing bodies at 17.

The cement used for the sealing body 17 is water-proof Portland cement or the equivalent, usually the same as is used in making the sections 10 and 11. By the term "cement," I intend to include not only pure cement, but cement which may contain sand or other materials admixed therewith and which do not interfere with a binding, joining, and water-proof action and connection.

In actual practice, the weight of the closure 11 plays an important part in obtaining the filling of the grooves 14 and 15 with the sealing cement 17 since such closure 11 weighs on the order of 400 to 500 pounds and the sealing cement is thus subjected to such weight which produces great pressure, causing the sealing cement to fill and intimately engage the grooves 14 and 15 and any surplus to rise above the grooves as best shown in Figure 7 at 18 to thus extend the area of binding and water-proof sealing since the material at 18 will bind with the adjacent side walls of the rib 12 and groove 13.

By cutting away the corners of the rib 12 at 16, so that such rib will be narrower at its lower end or base than above the grooves 15, I find that the rib more easily enters the body of the sealing plastic which produces the sealing bodies 17 and avoids trapping of air.

Various changes may be resorted to provided they fall within the spirit and scope of the invention.

I claim as my invention:

1. A vault, comprising a case and a lid, said case having a continuous groove in the upper edge thereof, a cementitious deposit for said groove, the case at the lower portion of the sidewalls of the groove being formed with lateral channels in opposed relation, said lid being provided with a continuous depending rib adjacent its edge for snug disposition in the groove, the lower portion of the rib provided with a downwardly flared formation having its greatest width less than the width of the rib proper to permit lateral displacement into the channels of the cementitious deposit when the rib is brought to bear against the bottom of the groove under the weight of the lid proper.

2. A vault comprising a case and a lid, said case having a continuous groove in the upper edge thereof, a cementitious deposit for said groove, the case at the lower portion of the sidewalls of

the groove being formed with lateral channels in opposed relation, said lid being provided with a continuous depending rib adjacent its edge for snug disposition in the groove, the lower portion of the rib provided with a downwardly flared formation having its greatest width less than the width of the rib proper to permit lateral displacement into the channels of the cementitious deposit when the rib is brought to bear against the bottom of the groove under the weight of the lid proper, said downwardly flared formation consisting of grooves in the lower edge portions of the rib, the lower wall portions of the grooves of the rib being shorter than their opposed portions to reduce that portion of the rib below the said edge grooves.

3. A vault comprising a case and a lid, said case having a continuous groove in the upper edge thereof, a cementitious deposit for said groove, the case at the lower portion of the sidewalls of the groove being formed with lateral channels in opposed relation, said lid being provided with a continuous depending rib adjacent its edge for snug disposition in the groove, the

lower portion of the rib provided with a downwardly flared formation having its greatest width less than the width of the rib proper to permit lateral displacement into the channels of the cementitious deposit when the rib is brought to bear against the bottom of the groove under the weight of the lid proper, sufficient clearance being allowed between the rib and the sidewalls of the case in said groove to permit forcing of a fine film of the cementitious deposit therebetween.
